(57) **CLAIM**

We claim the ornamental design for a labial pad, as shown and described.

DESCRIPTION

FIG. 1 is a top plan view of a labial pad embodying our new design;

FIGS. 2 and 3 are, respectively, left and right side elevational views of the labial pad illustrated in FIG. 1;

FIGS. 4 and 5 are, respectively, front and rear elevational views of the labial pad illustrated in FIG. 1; and,

FIG. 6 is a bottom plan view of the labial pad illustrated in FIG. 1.
